UNITED STATES PATENT OFFICE.

ROBERT T. FROST, OF DOWS, IOWA, ASSIGNOR TO THE FROST CONCRETE STONE COMPANY, OF DOWS, IOWA.

MACHINE FOR FORMING CONCRETE BUILDING-BLOCKS.

SPECIFICATION forming part of Letters Patent No. 772,563, dated October 18, 1904.

Application filed January 26, 1904. Serial No. 190,659. (No model.)

To all whom it may concern:

Be it known that I, ROBERT T. FROST, a citizen of the United States of America, and a resident of Dows, Wright county, Iowa, have 5 invented certain new and useful Improvements in Machines for Forming Concrete Building-Blocks, of which the following is a specification.

My invention relates to improvements in 10 machines for forming concrete building-blocks; and the object of my invention is to provide a machine which is very simple in construction and supplied with means whereby a change in the form of the mold may be 15 easily effected. These objects I have accomplished by the mechanism which is herein-after described and claimed and which is illustrated by the drawings hereto annexed, in which—

20 Figure 1 is a plan view of the machine, showing the mold adjusted to form a corner-block. Fig. 2 is a plan view showing a variation in the form of the mold for another style of block, and Fig. 3 is also a plan view showing the mold arranged for a third pattern of block.

Similar letters refer to similar parts throughout the several views.

I have in this machine emphasized the idea 30 of simplicity in design with cheapness and strength in construction. This is shown by the fewness of the parts, and the manner of their location and connection renders the parts of the mold readily adjustable for the purpose 35 of forming different patterns of building-blocks.

The bed-plate *o*, which is shown in plan in 40 all three views, has a centrally-located vertical upright *u*, which is utilized as a pivot for the inner interchangeable horizontally-movable sections of the mold *b*, *c*, *e*, *j*, and *u*. But two of these inner sections can be used at any one time to form the inner portion of the mold. Drop side sections *f*, *a*, and *d* are 45 hinged to sides of the bed-plate *o* by means of the hinges *k* and *l*, *v* and *y*, and *m* and *n*,

respectively. These drop sides form the outer portions of the mold, respectively, according to the particular arrangement of the inner sections. The drop sides may be fastened together at the corners when raised into position by means of lock-nuts *p*, *g*, and *h*. As shown, these lock-nuts work upon threads on the end of bolts which are pivoted at their other ends to studs affixed to the drop sides, 55 as shown.

The inner section *j* has two parts pivoted at *z* and may be moved horizontally when the side *f* has been dropped. The manner of releasing the sections of the mold from the 60 block is shown in all three figures by the dotted lines. In addition I have shown in Fig. 1 a method of molding blocks of a different configuration by means of placing sectional pieces across the interior of the closed- 65 up mold. The only operation necessary in order to change the form of the mold is to remove one or more of the inner sections and replace them by others of the desired shape, the upright pivot *u* keeping them in the 70 proper relation to each other.

Other shapes of the sectional parts of the mold than those shown may be substituted without altering the essential idea of my invention.

What I claim as new, and desire to secure by Letters Patent, is—

1. A machine for forming concrete building-blocks, consisting of a combination of adjustable sectional mold-plates, centrally pivoted to a bed-plate, and drop sides hinged to the edges of said bed-plate, substantially as shown and described.

2. A machine for forming concrete building-blocks, having an adjustable mold consisting of outer drop sides and two removable exchangeable inner sides, said inner sides pivoted on a bolt connected to the center of a bed-plate, and a bed-plate, substantially as shown and described.

3. A machine for forming concrete building-blocks, consisting of a bed-plate, outer

drop sides pivoted to said bed-plate, two
removable exchangeable inner horizontally-
movable sides pivoted to a bolt centrally con-
nected to said bed-plate, and a pivot-bolt cen-
trally connected to said bed-plate, said outer
drop sides furnished with fastening means,
substantially as shown and described.

Signed at Dows, Iowa, this 18th day of Jan-
uary, 1904.

ROBERT T. FROST.
